UNITED STATES PATENT OFFICE.

JACOB HARTMAN, OF PHILADELPHIA, PENNSYLVANIA, ASSIGNOR OF ONE-HALF TO A. H. MOORE, OF SAME PLACE.

FASTENING FOR RAILROAD-RAILS.

SPECIFICATION forming part of Letters Patent No. 338,066, dated March 16, 1886.

Application filed July 22, 1885. Serial No. 172,282. (No model.)

To all whom it may concern:

Be it known that I, JACOB HARTMAN, a citizen of the United States, residing in the city and county of Philadelphia, State of Pennsylvania, have invented a new and useful Improvement in Fastenings for Railroad-Rails, which improvement is fully set forth in the following specification and accompanying drawings, in which—

10 Figure 1 represents a top or plan view of a fastening for a railroad-rail embodying my invention. Figs. 2 and 3 represent views of opposite sides thereof. Fig. 4 represents a horizontal section in line $x\ x$ and $x'\ x'$, Fig. 5, all of 15 the said figure, except the parts designated by B' B' G' being on line $x\ x$, and the said parts B' B' G' being on line $x'\ x'$, and shown in position before being adjusted to allow of the insertion of the key. Fig. 5 represents a vertical 20 section in line $y\ y$, Fig. 2. Fig. 6 represents an end view thereof. Fig. 7 represents a horizontal section in line $x'\ x'$, Fig. 5, the ends of the rails being separated.

Similar letters of reference indicate corresponding parts in the several figures.

25 My invention consists of a fastening for a railroad-rail, the construction whereof is such that piercing the rail for spikes is avoided, and the rail is firmly held in position.

30 Referring to the drawings, A represents a railroad-rail, which is of usual construction. B represents a clamp, which engages with the rail, and C represents a key, which engages with said clamp and is secured to the stringer 35 D, for fastening the rail to the latter.

The clamp B consists of upwardly-projecting lips E E', which embrace the opposite sides of the base of the rail, a plate, F, which is connected with said lips and passes under 40 said base, and a downwardly-projecting lip, G, which embraces the stringer, the lip G being below the lip E. In the plate F and lip E' is a vertical opening, H, through which is passed the upper part of the key C, the latter 45 having an opening in its lower part for the passage of the screw J, by which the key is connected with the stringer. The inner faces of the lips E G are inclined, so as to take hold of the rail and stringer with a wedging effect,

and the inner face of the lip E has a shoulder, 50 E², which engages with a flange, A', on the rail A; consequently the rail is prevented from rising from the clamp B. The key is curved, so that its upper end locks with the wall of the lip E', and when it is connected 55 with the stringer by the screw J the clamp and key are firmly connected, and the key reliably attached to the stringer, it being evident that the clamp cannot disengage itself from the key, nor the key disconnect itself 60 from the stringer, and thus the rail is reliably fastened in position.

In the flange A' there are two openings, A², which coincide with the lugs B', formed in the clamp B by the openings H and shoulder G'.

When the rail is placed on the plate F, it is primarily fitted to the lip E, and then lowered to full extent, the portion A³ of the flange A', between the openings A² thereof, entering the 70 opening H, and the lugs B' enter the openings A². The rail or clamp is then shifted or moved lengthwise, whereby one of the lugs B' rests on the solid portion of the flange A' and another one thereof on the portion A³, 75 thus causing the shoulder E² of the lip E' to engage with or rest on the flange A' of the rail, and the opening H of the plate to coincide with one of the openings A² of the flange A'. The key is now passed through the opening H, and likewise one of the openings A², 80 and secured to the stringer, the fastening of the rail thus being completed, it being seen that actual spiking of the rail is avoided.

I am aware that it is not new to secure a rail 85 by a clamp having a fastening-piece secured thereto by a key, and such I do not claim.

Having thus described my invention, what I claim as new, and desire to secure by Letters Patent, is—

1. A railroad-rail fastening consisting of a clamp having lips which engage with the rail and stringer, and provided with a key, which passes through a vertical opening in the clamp and is secured to the stringer, substantially 90 as described.

2. The clamp B, formed with upwardly-projecting lips E E', a downwardly-projecting

lip, G, and a base-plate, F, in combination with a fastening-key, substantially as described.

3. The clamp B, having a vertical opening, H, shoulder E', and lugs B', and the rail having a flange, A', with openings A², substantially as and for the purpose set forth.

4. A clamp having a vertical opening, H,

and the key G, interlocking with the wall of said opening and connectible with a stringer, substantially as described.

JACOB HARTMAN.
